UNITED STATES PATENT OFFICE.

PAUL KAROL, OF BAGGALY, PENNSYLVANIA.

HAIRPIN.

Application filed December 28, 1918, Serial No. 268,686. Renewed August 14, 1922. Serial No. 581,844.

To all whom it may concern:

Be it known that I, PAUL KAROL, a citizen of Poland, residing at Baggaley, in the county of Westmoreland and State of Pennsylvania, have invented new and useful Improvements in Hairpins, of which the following is a specification.

This invention relates to hair pins and has for its object the provision of a pin 10 of simple construction and attractive appearance which may be held in position within the hair against accidental displacement.

Another object of the invention is the provision of a hair pin whose length may be adjusted to suit the convenience of the user, and whose width may be also controlled by bending the pin, so that the hair 20 may be securely held in either a tight or loose condition as desired.

Further objects and advantages of this invention will appear as the following description is read in connection with the accompanying drawing, in which:—

25 Figure 1 is a plan view of a hair pin constructed in accordance with the invention, and shown in closed position.

Figure 2 is a similar view with the parts separated.

30 Figure 3 is an enlarged sectional view through the ferrule end of the hair pin.

Figure 4 is a plan view of the modified form of the invention.

Figure 5 is an enlarged view of one end 35 of the pin showing a further modified construction.

Referring in detail to the form of the invention shown in Figures 1, 2 and 3, the hair pin is formed in three sections, one of 40 which includes a tubular sleeve 10 which is provided at one end with oppositely extending curved wings 11 formed of flat flexible metal or flexible wire, as desired the latter being preferred. These wings 45 extend inwardly or toward the opposite end of the sleeve 10 and are adapted to engage in the strands of the hair.

Fitting within the sleeve 10 is a connecting bar 12 which is of a diameter to snugly 50 fit and frictionally engage the tubular sleeve so as to be held in adjusted position. Formed on one end of the bar 12 is a ball 13 which is adapted to engage a socket 14 formed with a ferrule 15, so that the latter

may be removably but securely held in position upon the end bar. The ferrule 15 is provided with wings 16, similar to the wings 11 previously described and when the various parts of the pin are assembled these wings will move inward or toward one another.

The sleeve 10, the connecting bar 12 and ferrule 15 provide a hair pin which may be easily placed in the hair, it may be adjusted to suit the convenience of the user. The 65 wings being flexible they may be bent so as to engage the strands of the hair and hold them in a tight or loose condition.

The form of the invention shown in Figure 4, is similar in all respects to that shown 70 in preceding figures, except that only one wing 17 is provided at each end of the pin.

The form of the invention shown in Figure 5 is different from the previously described form, in that the wings 18, which are 75 carried by the sleeve 19 are secured through the medium of a ferrule 20 and securing the said ferrule around the reducing extremity 21 of the sleeve 19.

Various other changes may be made in 80 the form, proportion and minor details of construction of the invention and the right is here reserved to make such changes as properly fall within the scope of the appended claim.

In the use of the pin, the connecting bar 12 is inserted in the sleeve 10 and the latter is placed in the hair whereupon the opposite or curved end of the pin may be secured upon the connecting bar and the pin adjusted to proper length. The wings may 90 then be bent into shape.

Having described the invention what is claimed:—

A hair pin comprising an elongated tubular member, oppositely extending inwardly curved members carried at one end of the tubular member, a socketed member, oppositely extending inwardly curved members carried by the socketed member, expandible 100 spring entrance jaws extending from the socketed member, a bar adapted for frictional engagement with the tubular member and a ball located at one end of the bar for engagement with the socketed member. 105

In testimony whereof I affix my signature.

PAUL KAROL.
